UNITED STATES PATENT OFFICE.

BENJAMIN BRODIO, OF NEW YORK, N. Y., ASSIGNOR TO THE SUPERHEATER COMPANY, OF NEW YORK, N. Y., A CORPORATION OF DELAWARE.

BOILER WITH SUPERHEATER.

1,417,023.

Specification of Letters Patent. Patented May 23, 1922.

Application filed May 9, 1918. Serial No. 233,448.

To all whom it may concern:

Be it known that I, BENJAMIN BRODIO, a citizen of the United States, and resident of the city of New York, State of New York, 5 have invented certain new and useful Improvements in Boilers with Superheaters, of which the following is a specification.

This invention relates to boilers with superheaters and more particularly to 10 boilers comprising water tubes arranged so that they form two groups defining a space between them in the lower part of which is located the furnace.

It is the purpose of my present invention 15 to make provision for a superheater in such boilers capable of superheating steam to a high degree and yet properly protected against excessive heat.

The invention will be readily understood 20 from the following description which is to be read in connection with the accompanying drawings forming part hereof. In the drawings, Fig. 1 is a transverse section, and Figs. 2 and 3 are longitudinal sections with 25 portions omitted on lines 2—2 and 3—3 respectively of Fig. 1 of a boiler of this type with my device in place; Fig. 4 is a section, on an enlarged scale on line 4—4 of Figs. 1 and 2, showing a detail; Fig. 5 is a view 30 similar to Fig. 1 of a modification shown in a different form of boiler; Fig. 6 is a section on line 6—6 of Fig. 5; Fig. 7 illustrates a modification.

Reference will first be made to the form 35 of my device shown in Figs. 1 to 4. Here the groups of diverging water tubes 1, 1 are connected to upper drums 2, 2 and lower drums 3, 3; and define between them the space 4 in the lower portion of which is located the furnace. On each side of these 40 inclined groups of tubes are vertical groups 5, connected to upper drums 6 and lower drums 7. Together with groups 1 the groups 5 define the two triangular spaces 8. The 45 drums 9 are located between drums 2 and 6 on either side, and communicate with them by pipes. Baffles 10 close the spaces between laterally adjacent groups of tubes so that gases from furnace 4, to reach exits 50 11, are forced to pass among the tubes of the various groups and through the spaces 12 between the outermost tubes of each group (see Fig. 3).

The boiler is enclosed by the setting 13. 55 The structure thus briefly described is a

commercial form of boiler well known to those skilled in this art, and has not been modified or improved by me.

In a boiler of this type I propose to install 60 a superheater in the manner now to be described.

In order to obtain the high degree of superheat which is required to obtain the highest efficiency in the operation of engines without unduly increasing the size of the 65 superheater, the superheater must be located so that gases from the furnace reach it before they have been cooled appreciably or at all by contact with water-cooled surfaces. On the other hand, protection against the 70 intense radiant heat from the furnace must be provided to avoid injury to the superheater. I attain these objects by my invention.

I locate a superheater 14, of any desired 75 construction, in the upper part of space 4, where it will be swept by hot gases from the furnace that have not been cooled at all or to any appreciable extent by contact with boiler surfaces. To protect the superheater 80 against the intense radiant heat from the furnace, which would be likely to injure it particularly during possible temporary interruptions of steam flow through the superheater, two arches 15 and 16 are provided, 85 both of them located below the superheater, one above the other, and relatively staggered, so that together they intercept the radiation, but flow of gases to the superheater between them and around them is 90 free to occur.

In order to regulate the gas flow over the superheater, the hood 17 and damper 18 are provided. This hood has the shape, in cross-section, of an inverted V, one side being provided with an opening 19. Extending inward from the lower end of this opening toward the other leg of the inverted V, but terminating short of it, is the horizontal wall 20. This wall is above the superheater. 100 Slidable through a slot 21 is the damper 18, referred to above, which in its lowest position, completely interrupts the flow of gases through the hood 17 and over the superheater 14, and in intermediate positions 105 checks it more or less. This damper is preferably made in several sections, as shown in Figs. 2 and 3, each section sliding in grooves 22, 22 of the posts 23.

In Fig. 2, the dampers in the left half of 110

the boiler are shown completely lowered and in the right half they are shown partly lowered. When the dampers are partly or wholly lowered, the flow of gases over the 5 superheater is evidently partly or completely interrupted, and the danger of over-heating it can be averted. This is necessary particularly during periods when no steam is flowing through the superheater, as while the 10 boiler is being fired up, or when the engine is temporarily stopped.

If desired, the steam to be superheated may evidently be carried directly to the 15 superheater 14 from the drums 9 of the boiler. In my preferred form, however, as herein illustrated, I first carry the steam from each drum 9 through pipes 25 to a 20 superheater 24, one such superheater being placed in each of the spaces 8. The gases 25 which come into contact with these two superheaters 24, 24 have been cooled to a great extent by passing over boiler surfaces, and the steam receives only a preliminary superheating in them. It is then conveyed by pipes 26, 26 to the inlet header 27 of 30 superheater 14. From superheater 14 the finally superheated steam is carried off by pipe 28.

The steam area, that is the sum of the several parallel steam-paths, in superheater 14 is made smaller than the sum of the two steam areas of superheaters 24—24, in order to increase the velocity of steam flow through 35 superheater 14. By doing this the rate of carrying off the heat from the superheater, and so cooling it, is increased, and the danger of overheating it is lessened. This feature of increasing the velocity of the steam in that section of a two or more stage superheater which is in the hotter zone is evidently not limited to this particular form 40 of boiler or arrangement, but is of rather general application. It may be pointed out that the stage of the superheater in the cooler 45 region need not be in two sections, but may be in more, or may be in one; and that instead of two, there may be more than two stages. In the present case the two sections 24, 24 are in effect one superheater and may 50 be so considered for convenience. Applications of the feature just spoken of will occur in practice in various connections and need not be more fully described here.

Evidently the superheaters 24, 24 need 55 not be of any particular design. I prefer to make them of separate, readily detachable, looped units, secured to a bi-chambered header, and make provision for ready removal of a unit from the setting after it has 60 been detached from its header. This provision consists in the slot-shaped openings 29, 29, which of course are normally closed by doors.

The slots 29 are parallel to the planes of 65 the superheater units; and they lie opposite

spaces 29^a. When a unit is to be removed, its connection to the headers is broken, and it is then raised above the other units and brought opposite the slot 29, through which it can be removed. If the boiler is close to 70 a wall, or to the setting of the next boiler, the unit can, during its removal, be given the position indicated in dotted lines in the left half of Fig. 3, i. e. it can be removed diagonally upward, a portion of it projecting 75 downward into space 29^a during this removal.

In Fig. 5 I show my invention applied to a boiler of a different type, but sharing with the one described above the characteristic 80 of having two downwardly diverging banks of tubes defining a furnace space between them. These groups, 1^a, 1^a are secured to an upper drum 30 and two lower drums 31, 31. Two other upper drums, 32, 32, lie at either 85 side of drum 30, and are connected to it by water and steam pipes, and to the drums 31 by banks of tubes 5^a, 5^a. Appropriate baffling directs the products of combustion over the banks 1^a, down through the spaces 8^a 90 between the banks 1^a and 5^a, among the tubes 5^a, and so to the outlets 11, 11. This boiler is of a previously known design.

I place my superheater here also in the upper part of the space between the banks 95 1^a. The arrangement will be seen to be very similar to the one above described. A variation is introduced in the means for protecting the superheater against the direct radiation from the furnace. The means here used 100 for this purpose are two sets of fire-bricks, arranged as will be clear from Figs. 5 and 6. Each set is made up of a number of pairs of bricks 33, their outer ends resting on ledges 34 in the walls 35, and their inner 105 ends meeting each other. The bricks are each somewhat longer than half the distance between the walls 35. The pairs of each set are spaced, and the spaces of one set are staggered relatively to those of the 110 other.

If preferred, the construction of Fig. 7 may be used. Here a third wall 36 is placed between the other two, and the inner ends of the bricks rest on ledges 37 of this middle 115 wall. The bricks 33 are horizontal in this case.

Superheaters 24 are placed in spaces 8^a, as in the case first described, but a variation is introduced in the connections. Instead 120 of carrying the steam first through superheaters 24 and then for a final heating through superheater 14, the order is here reversed, the steam being first carried by pipes 25^a, 25^a and 25^b to the superheater 14, and 125 from it, by means of pipes 26^a, 26^a to superheaters 24, 24, whence it leaves by pipes 28^a, 28^a for the points of consumption. This reversed order is desirable in some cases and may evidently be employed in the case first 130

described. On the other hand the order used there may if desired also be used here.

What I claim is:—

1. In a boiler the combination of two downwardly diverging banks of tubes, a furnace in the lower part of the space between the banks, a superheater in the upper part, means below the superheater to intercept the direct radiation from the furnace but permitting the passage of hot gases to the superheater, and a hood over the superheater provided with a dampered opening at one side.

2. In a boiler the combination of two downwardly diverging banks of tubes, a furnace in the lower part of the space between the banks, a superheater in the upper part, a second superheater on the outer side of one of the banks of tubes, pipe connections from the steam space of the boiler to one of the superheaters and from it to the other superheater, means below the first superheater to intercept the radiation from the furnace but permitting hot gases to pass from the furnace to the first superheater, a hood over the superheater provided with a dampered opening at one side near its top.

3. In a boiler the combination of two downwardly diverging banks of tubes, a furnace in the lower part of the space between the banks, a superheater in the upper part, means to intercept direct radiation from the furnace toward the superheater but permitting the passage of hot gases to it, a hood over the superheater comprising two walls substantially parallel to the two banks of tubes respectively, one of these walls extending higher up than the other,

a horizontal partition extending from the top of the shorter wall toward the other but terminating short of it, thus leaving an exit for hot gases that have passed over the superheater, and a damper to control this exit.

4. In apparatus of the class described, the combination of a wall having a slot, a plurality of superheater units, each comprising a plurality of pipe lengths and all its parts lying in a single plane, said units lying in parallel planes and in a space adjacent to one end of the slot, there being a free space in the group of units in alignment with the slot wide enough so a unit may be inserted into it; whereby, during removal and replacement of a unit, it may be brought into a position such that it projects into the space, diagonally through the slot, and out into the space outside of the wall.

5. In apparatus of the class described, the combination of a vertical wall having a vertical slot, a plurality of superheater units, each comprising a plurality of pipe lengths and all its parts lying in a single plane, said units lying in vertical planes in a space adjacent to the lower end of the slot, there being a free space in the group of units in alignment with the slot wide enough so a unit may be inserted into it; whereby, during removal and replacement of a unit, it may be brought into a position such that it projects into the space, diagonally upward through the slot, and out into the space beyond the wall.

BENJAMIN BROIDO.
